United States Patent Office

Des. 178,560
Patented Aug. 14, 1956

178,560

ARTIFICIAL LURE

David M. Wiegand, Fort Worth, Tex.

Application September 7, 1954, Serial No. 32,183

Term of patent 7 years

(Cl. D31—4)

FIG. 1.

FIG. 2.

FIG. 3.

Figure 1 is a side elevational view of an artificial lure showing my new design;

Figure 2 is a top plan view; and

Figure 3 is a front elevational view thereof.

The dominant feature of my design resides in the full line portion of the drawing.

I claim:

The ornamental design for an artificial lure, as shown and described.
